The ornamental design for a box, substantially as shown and described.

DESCRIPTION

FIG. 1 is a top plan view of a box showing my new design;

FIG. 2 is an end elevational view thereof;

FIG. 3 is a bottom plan view thereof;

FIG. 4 is an elevational view looking from the right side of FIG. 1, the opposite side being substantially the same in appearance;

FIG. 5 is a view in cross-section taken along the lines

5—5 of FIG. 1; and

FIG. 6 is a view in cross-section taken along the lines
6—6 of FIG. 1.
